UNITED STATES PATENT OFFICE.

AMOS H. SMITH, OF BROOKLYN, NEW YORK, ASSIGNOR TO AMERICAN BANK NOTE COMPANY, A CORPORATION OF NEW YORK.

UNDERSURFACE PRINTING-MACHINE.

1,261,171.

Specification of Letters Patent.

Patented Apr. 2, 1918.

Application filed November 29, 1913, Serial No. 803,873. Renewed October 18, 1917. Serial No. 197,350.

To all whom it may concern:

Be it known that I, AMOS H. SMITH, a citizen of the United States, residing at the borough of Brooklyn, in the city of New York, county of Kings, and State of New York, have invented certain new and useful Improvements in Undersurface Printing-Machines, of which the following is a specification, reference being had therein to the accompanying drawings, which form a part thereof.

My invention relates to undersurface printing machines, and more particularly to a type thereof adapted for multi-color work.

While it is old in the printing arts to provide a printing machine adapted to produce work in a plurality of colors at a single impression or by a sequence of impressions, there has, to the best of my knowledge, never been made an attempt to produce a printing machine by means of which an imprint in a plurality of colors may be made at one impression, from an intaglio, engraved or undersurface plate.

Heretofore, multi-color work in the art of printing from intaglio, engraved or undersurface plates has always been done by the use of a plurality of plates, each plate bearing thereon a portion of the design to be printed in a color, the completed imprint being secured by a plurality of impressions.

It is true that an art or method has been heretofore devised, by which an imprint in a plurality of colors may be made from a plate at a single impression, nevertheless, by this method or art, the plate was inked and finished by hand, and the impression was made in an ordinary, well known undersurface printing press.

The difficulties to be surmounted in the construction of a machine made in accordance with my invention are the application of inks of different colors to different portions of a plate without mixing inks of different colors upon the inking rollers; the removal of the ink from the top or non-printing surface of the plate without drawing ink from the lines or mixing inks in the lines; and the wiping and polishing of the plate under conditions which will avoid the mixing of inks along the line of demarcation between the portions of the plate inked in different colors in a degree which

would materially vary the appearance of 55 the imprint.

With these conditions in mind, I have by my invention provided a continuously operating mechanism by which a plate may be completely inked with different portions thereof in different colors, without mixing the inks upon the inking rollers in a manner which would vary the tone quality of the ink during a continued run. In conjunction with this mechanism, I provide means 60 whereby the ink upon the top or non-printing surface will be automatically removed in a manner and to an extent so that the proper finish or wipe and polish may be given to the plate without mixing the inks along the 65 line of demarcation of the portions of the plate inked in different colors, which would preclude the production of a commercial product.

By arranging the inking, cleaning or 75 transfer, and wiping mechanisms so that they are successively operative upon a plate, I am enabled to produce an imprint in a plurality of colors, at a single impression, by purely mechanical means and without 80 materially reducing the speed of operation, or capacity, of the press.

In order to avoid the mixing of the inks in the process of cleaning the top or non-printing surface, or transferring the ink 85 deposited thereon therefrom, I constantly clean the transfer rollers so that they will present a surface substantially free of ink upon each application thereof to the plate. Preferably, I accomplish this result by the 90 transfer of ink from said roller to a second roller in constant contact therewith, which roller is subjected to the action of a scraping or rubbing mechanism, or both, so as to keep its surface clean.

Some such construction is desirable because while the inking rollers are operative only with relation to one color, the cleaning or transfer rollers with each actuation thereof, are coated with a plurality of colors, and unless perfect register were secured, there would be a mixing of colors in succeeding plates.

Furthermore, the quantity of surface ink removed is such that after a few impressions, were not the cleaning or transfer roller constantly cleaned, the accumulation of ink thereon would be sufficiently great to

prevent the removal of a sufficient quantity of ink from the plate to permit the application of wiping and polishing cloths thereto without a substantial variance in the color 5 tones through the mixture of inks in the lines of the plate.

By my improved mechanism, while the inking of the plate and its subsequent preparation for the making of the imprint are 10 accomplished by a sequence of operations, the actual imprint is made at a single impression by means of the ordinary printing couple, consisting of a support for the plate and a platen or D-roll.

15 My invention consists primarily in an undersurface printing machine embodying therein inking means, adapted to apply inks of different colors to different portions of an intaglio or engraved plate, means adapted 20 to remove ink from the top or nonprinting surface of a plate, and a printing couple whereby an imprint in a plurality of colors is made at one impression from a plate; and in such other novel features of construction 25 and combination of parts as are hereinafter set forth and described, and more particularly pointed out in the claims hereto appended.

Referring to the drawings:—
30 Figure 1 is a plan view of a machine embodying my invention, portions of the driving means and actuating means for the wiper and polisher being omitted, as these are well known in the art and form no part 35 of this invention;

Fig. 2 is an elevation of that side of the machine upon which the inking mechanism is positioned;

Fig. 3 is an end elevation of the machine, 40 showing that end upon which the surface ink removing mechanism is situated;

Fig. 4 is a view of the side of the machine opposite to that shown in Fig. 2;

Fig. 5 is a view of the end of the machine 45 opposite to that shown in Fig. 3;

Figs. 6, 7 and 8 are detail views of the inking rollers, showing, conventionally, the inking portions thereof; and

Figs. 9, 10 and 11 are views of a plate, 50 showing the different colors as applied thereto from the inking rollers.

Like letters refer to like parts throughout the several views.

In the embodiment of my invention shown 55 in the accompanying drawings, I have illustrated it in connection with a well known type of plate printing press, generally known as the "Milligan" press.

This type of machine comprises a frame 1, 60 the top plate 2 of which is quadrangular and has parallel ways 3 and 4 extending about same. Mounted to travel in said ways is a plurality of plates or beds, 5, 6, 7 and 8, usually four in number, which beds or 65 plates are connected by a swivel connection,

not shown, with a driving chain 9, common thereto. At one side of the frame in this older type of machine, is a D-roll or impression cylinder; upon another side thereof is an inking mechanism; upon the third side 70 thereof is a wiping and polishing mechanism; while the fourth side is unobstructed to afford opportunity for the pressman to give a hand finish to each plate if the surface thereof is not thoroughly cleaned by the 75 wiping and polishing cloths.

This machine is substantially square, in which respect my present machine differs therefrom, the top plate being oblong, thus reducing the lineal traverse of the plate carriers, and increasing the capacity of the machine without increasing the rate of speed at which the plate carriers travel. 80

This feature is one of considerable importance in that the maximum speed of traverse 85 of the carriers is determined by the interval of time required to secure the desired imprint.

By the construction heretofore referred to, a practically continuously operating press is 90 secured, the capacity of which is limited solely to the actual time required to make an imprint, and that interval represented by the distance which the plates 5, 6, 7 and 8 are spaced apart on the driving chain. 95

I have illustrated my invention in connection with a machine of this type because there is ample space in which to locate the various mechanisms incorporated in the machine and because the invention can be practised to excellent advantage with a flat bed, undersurface machine. 100

It is not my intention, however, to limit the invention to any particular type of machine, it being apparent that the essential 105 characteristics of my invention may be adapted to other types of machines than that shown, and secure the desired results.

While in the accompanying drawings I have shown a particular relation of the various mechanisms operating upon the plate, 110 the arrangement shown is merely one of expediency and may be varied to meet the requirements of any particular type of machine in which my invention may be incorporated. 115

The essentials of my machine are an inking mechanism by means of which inks of different colors may be applied to different portions of intaglio or engraved plates; a 120 mechanism for removing the ink upon the top or non-printing surface of the plate, which in the form of the invention shown in the drawings includes an ink transfer mechanism as well as a wiping and polishing 125 mechanism; and a printing couple, which embraces the support for the plate, and the platen or D-roll, which mechanisms are operative upon a plate successively in the order above specified. 130

In the specific form of the invention shown, I employ an inking roller 11, adapted to have impressed thereon by means of a transfer roller 12, an ink design approximating in contour only those portions of a completed design to appear in any particular color. The transfer roller, 12, is inked by means of any desired inking mechanism, 13.

The roller 11 is similar to an ordinary off-set printing roller, being provided with a flexible surface, and the roller 12 may be provided with a planographic printing surface, or a raised or cameo printing surface, as desired, the latter being preferable, in 15 that no damping mechanism is required in connection therewith. This mechanism above referred to is capable of inking the plate in one color only, and in order to permit the inking of the plate in a plurality of 20 colors, I provide a plurality of such mechanisms, three in number, being shown in the accompanying drawings. Each of these inking mechanisms is adapted to apply ink of a different color to the plate, the designs upon the inking rollers 14 and 17 being substantially identical in contour with portions of the plate, differing from that represented upon the roller 11 and from each other.

The designs upon these three rollers, in the aggregate, constitute the complete design to be printed. The roller 14 receives its ink from a transfer roller 15, which in turn is inked from the inking mechanism 16; while the inking roller 17 receives its ink 25 from the transfer roller 18, which in turn is inked by the inking mechanism 19. While these inking rollers are arranged to act consecutively upon a plate, there will be no blending of colors upon any of these rollers, 30 as each receives its imprint for inking purposes from an entirely independent source, and the different designs upon these rollers respectively are adapted to register one with the other so that even though the non-inking 35 surface of a roller pick up ink deposited upon the top surface of a plate by another roller, this will have no effect other than a tendency to pack the lines of the plate to be inked in such color or colors.

After a plate has been brought into the operative relation to each of the inking rollers, 40 11, 14, and 17, the entire design appearing thereon will have been inked, portions thereof in one color, and portions thereof in another, 45 there remaining upon the top or non-printing surface of the plate a film of ink of varying colors which must be removed.

After each plate has left the inking rollers, it passes to the mechanism or means for 50 removing this surface ink. In the form of the invention shown in the drawings, I remove the major portion of this ink by "lifting" it from the surface, or transferring it to a transfer roller 20, or a plurality of such rollers in order to remove as much of this

ink as possible prior to the final wiping and polishing process.

I employ a roller for "lifting" this surface ink because of the necessity for removing the ink without having rubbing contact 70 between the means employed and the surface of the plate in order to minimize any possibility of this surface ink being carried beyond that portion of the design to appear in that color, or avoid the mixing of the inks 75 upon the surface of the plate. By using a roller, the continuity of the operation of the machine is not interrupted, and a reduction in the speed or rate of traverse of the plate carriers is unnecessary.

Inasmuch as the transfer roller 20 will have inks of all colors applied thereto, it is apparent that unless a perfect register of the design impressed thereon by succeeding plates is secured, there would be a tendency 80 of the transfer roller to mix the inks upon the surface of a plate with those upon its surface, and thus destroy the effect of the imprint. To avoid this condition, and a necessity for securing this perfect register, 85 however, I provide a second roller 21, in constant engagement with the roller 20 and adapted to receive the ink therefrom.

While the roller 20 is preferably formed of a composition the same as ordinary inking rollers, the roller 21 is preferably made of metal so that the surface thereof may be continuously cleaned by means of the scraper 22 and the rubber 23. By this means, the roller 20 is constantly cleaned, so that substantially no ink will be contained thereon 100 upon its initial application to any plate.

In the accompanying drawings, I have shown two such mechanisms for transferring the surface ink from the plate, the second transfer roller being indicated at 24, the cleaning roller at 25, the scraper at 26 and the rubber at 27.

Upon leaving the transfer rollers 20 and 24, each plate 5, 6, 7 or 8 comes into the operative relation with the wiping and polishing mechanism by means of which the final finish is given to the plate by the removal of any ink remaining upon the top or non-printing surface. This mechanism 110 comprises a wiping pad 28, provided with the usual movable cloth 29, and a polishing pad 30, provided with the usual polishing cloth 31.

The specific wiping and polishing mechanisms shown are old and well known in this art, and a detailed description thereof will therefore not be entered into, particularly as the detailed construction of the wipers and polishers is immaterial to the invention 115 and any form of such may be employed.

While, considered broadly, the wipers and polishers have the same function as the wipers and polishers ordinarily employed in undersurface printing machinery, the condi- 120 125 130

tions under which they operate are such that the effect secured thereby differs somewhat from that secured by the ordinary wipers and polishers in the respect that, because of the small quantity of ink which they are required to remove, the wiper does not become saturated with the ink, as with the ordinary wiper, and will not have the same effect in packing the lines of the plate. In fact, the wiper 28-29 will be practically nothing more than a rough polisher, while the polisher 30-31 will in a measure take the place of the ordinary hand finish.

The pads 28 and 30 may be actuated in any desired manner, the mechanism for actuating same not being shown in the accompanying drawings. These mechanisms are arranged upon the long side of the machine, opposite the inking mechanism.

Upon the front end of the machine, or opposite the transfer rollers, is a D-roll 32, of ordinary construction, which is actuated in the usual and well known manner.

The various inking rollers 11, 14, and 17 are all simultaneously driven in the same direction and at the same speed, in any desired manner, as by the gears 33, the rollers 11 and 12, 14 and 15, 17 and 18, being geared together so as to move in unison and thus insure accuracy in the setting of the machine for register.

The transfer rollers 20 and 24 are also preferably positively driven so as to avoid any possibility of such slippage as would result in a rubbing action upon the plate.

Any desired mechanism as the gear and chain mechanism 34 may be employed for this purpose.

The manner of actuating the various elements forms no part of this invention, and in the accompanying drawings I have shown same in a merely conventional manner.

While I prefer to remove the ink from the top or non-printing surface after all of the colors have been applied thereto, because this simplifies the structure of the machine and reduces the number of parts, I do not contemplate restricting myself to this particular construction, it being merely necessary, considering my invention in its broader aspects, to provide means for removing said surface ink after the inking rollers have applied it to the non-printing surface and prior to subjecting the plate to the action of the wiping and polishing cloths.

Nor do I intend to limit myself to the joint use of a wiping cloth and a polishing cloth, as under some conditions either of these may be dispensed with.

The operation of the herein described machine is substantially as follows:—

A plurality of similar plates having been mounted upon the traveling carriers or beds, 5, 6, 7 and 8, these carriers or beds receive a

unidirectional, continuous movement from the chain drive 9, so as to bring each plate successively into the operative relation with the inking, cleaning, wiping and polishing, and D-roll mechanisms. 70

Before beginning a run, ink transfer rollers 12, 15 and 16, bearing upon their surfaces, respectively, different portions of the design appearing upon the plates upon the carriers or beds, 5, 6, 7 and 8, are assembled 75 in the machine and set so that the ink applied by said rollers to their inking rollers 11, 14 and 17, will come into register with that portion, or those portions, of the plate bearing portions of the design corresponding with those indicated upon the said transfer rollers. Hence, as each of the plates upon the carriers or beds 5, 6, 7 and 8 passes under the inking rollers 11, 14 and 17, these rollers will apply to the plate inks of different colors, the entire surface of the plate being inked after passing the roller 17. 80

If desired, but two colors may be applied to the plate by the ink transfer rollers, the roller 15 being omitted and the roller 14 90 thus acting as a transfer roller to aid in cleaning the top or nonprinting surface of the plate. As each plate comes into the operative relation to the transfer rollers 20 and 24, these rollers having a peripheral 95 velocity equaling the lineal velocity of the plates, will, through engagement with the top surface "lift" or "pick up" the ink upon the nonprinting surface, while having a tendency to pack the ink in the lines of the 100 plate. The rotary movement of the transfer rollers 20 and 24 will avoid any rubbing contact of these rollers with the plate, thus avoiding mixing of the inks upon said top surface, or the piling of the ink in a manner 105 to spread it about the plate. Upon the continued rotation of each of the rollers 20 and 24, the ink upon the yielding surface thereof will be transferred to the ink receiving rollers 21 and 25, thus keeping the surface 110 of the rollers 20 and 24 substantially free of ink.

The scrapers 22 and 26 and rubbers 25 and 27 will remove the ink from the cleaning rollers 21 and 25, so that the surface thereof will always be conditioned to receive ink from the transfer rollers 20 and 24. 115

The plate after leaving the roller 24, will have its top surface substantially free of ink, although there will be a tendency for 120 the grain of the rollers 20 and 24 to leave a fine "stipple" upon portions of this top surface. It is because of this tendency to leave ink in minute quantities upon the top or non-printing surface that the wipers and 125 polishers are employed.

Under some conditions of use, this residue of ink will be very small, and under such conditions only a polishing cloth is needed, but where the quantity of ink is greater, it 130

is better to employ both a wiping and a polishing cloth, so as to avoid any "smudging" of the imprint.

After leaving the wiping and polishing cloths, the paper is fed to the plate in any desired manner, and an impression is made through the travel of the plate bearing the paper under and in engagement with the D-roll.

It will thus be observed that after a plate has left the wiping and polishing cloths, the lines thereof will be filled and packed with inks of different colors, so that an imprint in a plurality of colors will be made at a single impression.

It will also be observed that the inking of the plate in a plurality of colors and the cleaning of the top surface, are accomplished by a sequence of mechanisms operating successively upon each plate, thus making all of the functions of the machine automatic. The manner of applying ink to, and cleaning, the plate is such as to avoid any necessity for reducing the speed of operation of the press, and an imprint made thereon should present a design in a plurality of colors of substantially the same tone throughout as the ink used in the respective ink founts.

In other words, the mechanism for cleaning the top or non-printing surface of the plate is operative in a manner to avoid the mixing of the ink upon the surface of the plate, the sole tendency to so mix them being present at the wiping cloth. While there is a tendency on the part of the wiping cloth to mix the inks, the effect of such mixture will be over a very restricted area, being confined to substantially the line of demarcation between adjoining portions differing in color, under which conditions there will be merely a slight blending of one color into another, which will have no material effect upon the commercial value of the work done upon the machine. Where there is a substantial area of non-printing surface interposed between different portions of the design appearing in different colors, there will be no such tendency to blend one color into the other.

The design upon the plate or plates being made up of a large number of depressed lines, many of which are very fine, it is practically impossible to apply ink to the plate in a manner to cause it to enter the lines only without being applied to the non-printing surface. It is for this reason that the design upon the ink transfer rollers 12, 15 and 18 is made in a solid color, the outline of which only coincides with the portion of the design to be inked in that color.

While this manner of inking entails a loss of ink, nevertheless, a machine of the character herein described will effect a very substantial saving of ink over the present

methods of multi-color work, as each color is applied to only a portion of the plate, while by existing methods each color is applied to the entire surface of a plate.

It is not my intention to limit my invention to the details of construction shown in the accompanying drawings, it being apparent that such may be varied without departing from the spirit and scope of my invention and that without substantial modification, my invention may be applied to different types of machines.

Having described my invention, what I claim as new and desire to have protected by Letters Patent, is:—

1. An undersurface printing machine embodying therein a sequence of inking means adapted to successively apply inks of different colors to different portions of an intaglio or engraved plate, means adapted to bear upon but have no rubbing contact with the plate, whereby ink is removed from the top or non-printing surface of the plate, and a printing couple whereby an imprint in a plurality of colors is made at one impression from a plate.

2. An undersurface printing machine embodying therein inking means adapted to apply inks of different colors to different portions of an intaglio or engraved plate, means carrying a transfer surface adapted to operatively engage a plate without rubbing contact therewith, for removing the surface ink from the plate, a wiping mechanism operative upon the plate after said surface ink has been removed by said transfer surface, and a printing couple whereby an imprint in a plurality of colors is made at one impression from a plate.

3. An undersurface printing machine embodying therein a sequence of transfer rollers each having thereon in silhouette a portion of a design upon a printing plate, inking means associated with said transfer rollers respectively whereby said rollers are inked in different colors, a sequence of inking rollers in operative connection with said transfer rollers whereby the portions of the designs upon said transfer rollers are applied to said inking rollers respectively and are successively applied by said inking rollers to a plate, means adapted to bear upon but having no rubbing contact with the plate whereby ink is removed from the top or non-printing surface of the plate without materially blending the colors in the printing lines and a printing couple whereby an imprint in a plurality of colors may be made at one impression from a plate.

4. An undersurface printing machine embodying therein a sequence of transfer rollers each having thereon in silhouette a portion of a design upon a printing plate, inking means associated with said transfer rollers respectively whereby said rollers are

80

85

- inked in different colors, a sequence of inking rollers in operative connection with said transfer rollers each having a resilient surface adapted to receive ink from its transfer 5 roller and apply it to a plate whereby the portions of the designs upon said transfer rollers are applied to said inking rollers respectively and are successively applied by said inking rollers to a plate, means adapted 10 to bear upon, but having no rubbing contact with the plate whereby ink is removed from the top or non-printing surface of the plate without materially blending the colors in the printing lines and a printing couple whereby 15 an imprint in a plurality of colors may be made at one impression from a plate.
5. An undersurface printing machine embodying therein a plurality of inking rollers each having a resilient surface adapted to 20 receive ink and apply it to a plate, a transfer roller associated with each said inking roller and adapted to impress thereon a portion of a design upon a plate, inking means for said transfer rollers respectively, whereby inks of 25 different colors may be applied by said inking rollers respectively to different portions of an intaglio or engraved plate, means carrying a transfer surface adapted to operatively engage a plate without rubbing contact therewith, for removing the surface ink 30 from the plate, a wiping mechanism operative upon the plate after said surface ink has been removed by said transfer surface, and a printing couple whereby an imprint in a plurality of colors is made at one impression from a plate.
6. An undersurface printing machine embodying therein a plurality of adjacent inking rollers, a transfer roller associated with 40 each said inking roller and adapted to impress thereon a portion of a design upon a plate, inking means for said transfer rollers respectively whereby inks of different colors may be applied by said inking rollers respectively to different portions of an intaglio or engraved plate, means carrying a transfer surface adapted to operatively engage a plate after it has been inked in a plurality of colors, and without rubbing contact therewith, means operative upon 45 said transfer surface whereby ink is removed therefrom after each application to a plate, a wiping mechanism operative upon the plate after said surface ink has been removed by said transfer surface, and a printing couple whereby an imprint in a plurality of colors is made at one impression from a plate.
5. An undersurface printing machine embodying therein inking means adapted to apply inks of different colors to different portions of an intaglio or engraved plate, a 55 roller having a transfer surface adapted to remove ink from the top or non-printing surface of the plate, and a printing couple whereby an imprint in a plurality of colors is made at one impression from a plate.
7. An undersurface printing machine embodying therein inking means adapted to apply inks of different colors to different portions of an intaglio or engraved plate, a 60 roller having a transfer surface adapted to remove ink from the top or non-printing surface of the plate, and a printing couple whereby an imprint in a plurality of colors is made at one impression from a plate.
- 65 8. An undersurface printing machine embodying therein inking means adapted to apply inks of different colors to different portions of an intaglio or engraved plate, a roller having a transfer surface adapted to remove ink from the top or non-printing surface of the plate, means operative upon said last named roller whereby its surface is cleaned after each application to a plate, and a printing couple whereby an imprint in a plurality of colors is made at one impression from a plate.
9. An undersurface printing machine embodying therein inking means adapted to apply inks of different colors to different portions of an intaglio or engraved plate, a 10 roller having a transfer surface adapted to remove ink from the top or non-printing surface of the plate, a roller in engagement with, and adapted to receive the surface ink from, said last named roller, a scraper and a rubber acting thereon to continuously remove ink therefrom, and a printing couple whereby an imprint in a plurality of colors is made at one impression from a plate.
10. An undersurface printing machine embodying therein a plurality of adjacent inking rollers, a transfer roller associated with each said inking roller and adapted to impress thereon a portion of a design upon a plate, inking means for said transfer rollers respectively whereby inks of different colors may be applied by said inking rollers respectively to different portions of an intaglio or engraved plate, means carrying a transfer surface adapted to operatively engage a plate after it has been inked in a plurality of colors, and without rubbing contact therewith, means operative upon said transfer surface whereby ink is removed therefrom after each application to a plate, a wiping mechanism operative upon the plate after said surface ink has been removed by said transfer surface, and a printing couple whereby an imprint in a plurality of colors is made at one impression from a plate.
11. An undersurface printing machine embodying therein inking means adapted to apply inks of different colors to different portions of an intaglio or engraved plate, means carrying a transfer surface adapted to operatively engage a plate without rubbing contact therewith, for removing the surface ink from the plate, a wiping mechanism and a polishing mechanism successively operative upon the plate after said surface ink has been removed by said transfer surface, and a printing couple whereby an imprint in a plurality of colors is made at one impression from a plate.
12. An undersurface printing machine embodying therein a continuous track or course, a plate carrier or bed, means imparting unidirectional movement to said carrier or bed, a sequence of inking mecha-

nisms adapted to successively apply inks of different colors to different portions of an intaglio or engraved plate mounted upon said carrier or bed, means adapted to bear upon but have no rubbing contact with the plate, whereby ink is removed from the top or non-printing surface of the plate, and an impression cylinder arranged beyond said last named means whereby a plate upon

5 said carrier or bed will be successively inked, in a plurality of colors, finished, and brought into the printing relation to said impression cylinder.

13. An undersurface printing machine embodying therein a continuous track or course, a plurality of plate carriers or beds, means common to all said carriers or beds for imparting simultaneous, equal, unidirectional movement thereto, a sequence of inking mechanisms adapted to successively apply inks of different colors to different portions of intaglio or engraved plates mounted upon said carriers or beds, successively, means adapted to bear upon but have 25 no rubbing contact with the plate, whereby ink is removed from the top or non-printing surface of said plates successively, and an impression cylinder arranged beyond said last named means, whereby the plate upon

30 each of said carriers or beds will be successively inked in a plurality of colors, finished, and brought into the printing relation to said impression cylinder.

14. An undersurface printing machine embodying therein a quadrangular track or course, having two long sides and two short

sides, inking means arranged upon one of said long sides, adapted to apply inks of different colors to different portions of an intaglio or engraved plate, means adapted to remove ink from a plate arranged upon the short side of said track or course, wiping and polishing mechanisms arranged upon the other long side of said course, opposite said inking mechanism, and an impression cylinder or D-roll mounted above 40 said course intermediate said wiping and polishing mechanisms and said inking mechanism, and upon the short side of said track or course.

15. An undersurface printing machine embodying therein inking means adapted to apply inks of different colors to different portions of an intaglio or engraved plate, a plurality of rollers each having a transfer surface adapted to remove ink from the top or non-printing surface of the plate, means operative upon each of said last named rollers whereby its surface is cleaned after each application to a plate, and a printing couple whereby an imprint in a plurality of colors is made at one impression from a 45 plate.

In witness whereof, I have hereunto affixed my signature in the presence of two 50 subscribing witnesses, this 24th day of November, 1913.

AMOS H. SMITH.

Witnesses:

F. T. WENTWORTH,
EUGENE WHITING.
